[57] CLAIM

The ornamental design for a child carrier with grab bar and footwells for bicycle, as shown and described.

DESCRIPTION

FIG. 1 is a front perspective view of the child carrier with grab bar and footwells for bicycle showing our new design;

FIG. 2 is a rear elevational view thereof;

FIG. 3 is a side elevational view thereof;

FIG. 4 is a top plan view thereof;

FIG. 5 is a front elevational view thereof;

FIG. 6 is a bottom plan view thereof;

FIG. 7 is a side elevational view of a child carrier with grab bar and footwells for bicycle showing a second embodiment of our new design, the sole difference residing in the apertures in the sides thereof;

FIG. 8 is a side elevational view of a child carrier with grab bar and footwells for bicycle showing a third embodiment of our new design, the sole difference being in the configuration of the footwells thereof; and

FIG. 9 is a front elevational view of FIG. 8.

The broken lines of FIG. 1 are for illustrative purposes only and form no part of the claimed design.

The characteristic feature of our new design resides in the outwardly projecting footwells as seen in all views except FIG. 2 of the drawing.
